Patented Mar. 9, 1976

239,078

STATIONARY ROPE LOCK

Charles E. Hurney, Spirit Lake Iowa, assignor to
Berkley & Company, Inc., Spirit Lake, Iowa

Filed Feb. 8, 1974, Ser. No. 440,837

Term of patent 14 years

Int. Cl. D8—07

U.S. Cl. D8—108

FIG.1

FIG. 2

FIG. 3

FIG. 4

FIG. 5

FIG. 1 is a perspective view of a stationary rope lock, the broken lines being for illustrative purposes only; FIG. 2 is a top plan view of the design; FIG. 3 is a side elevational view of the design; FIG. 4 is a front elevational view of the design with the rear elevational view being identical thereto; and FIG. 5 is a bottom plan view of the design.

I claim:

The ornamental design for a stationary rope lock, as shown and described.
